UNITED STATES PATENT OFFICE

2,085,847

CONTAINER

Herman Carew, Easton, Pa., assignor, by mesne assignments, to Dixie-Vortex Company, Chicago, Ill., a corporation of Delaware

Application July 19, 1934, Serial No. 736,070

7 Claims. (Cl. 229—5.5)

My invention relates to new and useful improvements in containers and more particularly to a container formed of paper and adapted for holding liquids such as milk although it will be understood that the same might equally as well be used for holding other liquids, granules or the like.

The principal object of the invention resides in the provision of a novel form of closure adapted to be placed in position after the container has been filled and secured to prevent accidental displacement or leakage of the contents.

Another object of the invention consists in the provision of a novel form of closure adapted to be positioned within the end of the container and initially held by engagement of a portion of the body therewith and then sealed by the use of an adhesive or sealing material received in a recess formed in the closure.

Still another object of the invention resides in the provision of a novel form of closure adapted to be inserted in the end of the container, the closure being formed with an edge flange adapted to be engaged by an inturned portion of the body of the container, the closure being further provided with a recess to receive an adhesive or sealing material which, when hardened, securely holds and locks the inturned end of the container into tight sealing engagement with one face of the flange of the closure while at the same time holding the opposite face of the flange of the closure in tight engagement with the inner wall of the body.

With the above and other objects in view, which will appear as the description proceeds, my invention consists in the novel details of construction, and arrangement of parts, described in the following specification and illustrated in the accompanying drawing, and while I have illustrated and described the preferred embodiments of the invention, as they now appear to me, it will be understood that such changes may be made as will fall within the scope of the appended claims.

In the drawing:—

Fig. 1 is a top plan.

Fig. 2 is a side elevation with parts broken away.

Fig. 3 is a fragmental detail showing a body of the container with a closure in position ready for insertion into the end of the container.

Fig. 4 is a view similar to Fig. 3 with a closure inserted in the body of the container.

Fig. 5 is a view similar to Figs. 3 and 4 with the end of the body of the container folded into interlocking engagement with a closure; and

Fig. 6 is a fragmental detail showing the sealing element or material for holding and securing the closure into the body of the container.

In the drawing 1 indicates the body portion

of the container which is cylindrical in form and tapered, as shown more particularly in Fig. 2 of the drawing, to be of greater diameter at the normal bottom than at the normal top, the body being formed of paper folded into the shape 5 shown with the edge portions overlapped and sealed to provide the longitudinal seam indicated at 2. The smaller end of the body 1 will be closed by the disc 3 which has the inwardly directed flange 4, the flange being secured to the inner 10 wall of the body 1 by suitable adhesive and the end of the body being curled or folded inwardly to engage the outer face of the disc 3, as shown at 5 in Fig. 2 of the drawing.

Normally the opposite end of the container or 15 body will be left open for filling purposes and when filling the container will be inverted and supported by its smaller end portion closed by the disc 3. When filled with the desired material the closure disc 6 will be inserted into the end 20 of the body as shown in Fig. 4 of the drawing. This closure disc 6 is preferably of central concavo-convex shape with the convexed face extending inwardly of the body of the container this concavo-convex portion being indicated at 25 7. Extending around the concavo-convex portion is the relatively flat portion 8 with its edge bent to form the inclined flange 9, the edge of which in turn is bent to provide a vertical flange 10 with a groove or recess 11 between the inclined flange 9 and the vertical flange. When inserted into the end of the body 1, as shown more particularly in Fig. 4 of the drawing the outer face of the flange 10 will tightly engage the inner surface 30 of the body 1, this tight engagement being accomplished by pressing the closure into the tapered body. After the closure 6 has been positioned, as shown more particularly in Fig. 4 of the drawing, the end of the body 1 will be folded inwardly, as shown at 12, to extend over the end 40 of the vertical flange 10 and to engage the inner surface thereof. By reference to Figs. 3 and 4 of the drawing it will be seen that the vertical flange 10 is of somewhat less height than the flange 9 so that when the end of the body 1 is turned inwardly, as shown at 12, the end of the body will 45 be on the same plane as the straight portions 8 of the closure disc.

After the end of the body has been turned inwardly, as shown at 12, then high temperature 50 liquid adhesive and sealing material, indicated at 13, is placed into the recess 11 and permitted to harden. When it hardens it acts to hold and lock the inturned end 12 into tight sealing engagement with the inner face of the flange 10 and at 55 the same time holds the outer face of the flange 10 into tight sealing engagement with the inner surface of the body 1. After the material has hardened then the container may be inverted to what may be termed its normal position with its 60

larger end acting as a bottom therefor. Preferably the sealing material 13 is in the form of wax or similar material and forms what might be termed a lock. At times it might be desirable 5 to use a wedge in the form of a ring of wood, metal or possibly rubber, each of which would act in the same manner as does the wax or similar material.

From the above detailed description it is 10 thought that the construction of the container and manner of use will be clearly understood. As has been stated, the closure disc 3 is initially secured in one end of the body 1 and when filling the container the same will be positioned or inverted 15 to be supported by that end closed by the disc 3. This permits the container to be filled through the open end and then the closure disc 6 will be positioned and sealed as described. When thus sealed the container may be again inverted 20 to its normal position with the larger end acting as a bottom or support. The wedge formed by the material 13 acts as a lock and prevents the flange 10 of the closure 6 from breaking away from the wall of the body 1 and at 25 the same time prevents the inturned portion 12, of the body, from breaking away from its engagement with the inner face of the flange 10. As shown more particularly in Fig. 6 of the drawing, a certain amount of the material 13 enga- 30 ges around the end of the inturned portion 12 and acts as a further seal or adhesive therefor. The straight portion 8, of the closure 6, being on the same plane as the end of the body after being turned inwardly, as shown at 12, will 35 engage the support on which the container is held and thus act in supporting the closure 6 against the weight of the material in the container. I want to emphasize the fact that the hardened material 13 acts as a lock to prevent the disassociation of the co-related parts unless 40 the wedge or locking material is actually broken apart.

Preferably the container will be coated or treated with paraffin or the like and as the material 13 will preferably be introduced at a high 45 temperature it will melt the coating material originally placed on the wall or body of the container which aids in forming a tight seal.

Having fully described my invention what I 50 claim as new and desire to secure by Letters Patent is:

1. A container including a paper body, a closure adapted to be inserted in an end of the body, said closure including a flange and a recess adjacent thereto, the end of the paper forming the body being folded inwardly into engagement with the flange of the closure and into the recess thereof, and a plastic filler introduced into the recess of the closure to hold and lock the inturned end portion of the body into tight engagement 55 with the flange of the closure and the flange of the closure into tight engagement with the body.

2. A container including a paper body, a closure adapted to be inserted in an end of the body, said closure including a flange and a recess adjacent thereto, the end of the paper forming the body being folded inwardly into engagement with the flange of the closure and into the recess thereof, and liquid adhesive material placed in 60 the recess of the closure and adapted to harden to hold and lock the inturned edge portion of the body into tight engagement with the flange of the closure and the flange of the closure into 65 tight engagement with the body.

3. A container including a paper body, a closure adapted to be inserted in an end of the body, said closure including a flange and a recess adjacent thereto, the end of the paper forming the body being folded inwardly into engagement with the flange of the closure and into the recess thereof, and liquid adhesive material placed in the recess of the closure and adapted to harden to tightly hold and lock the inturned portion of the body into facewise engagement with the flange of the closure and the flange of the closure into like engagement with the body, said adhesive extending around and into engagement with the edge of the inturned portion of the body received in the recess of the closure. 10

4. A container including a paper body, a closure adapted to be inserted in an end of the body, said closure including a flange and a recess adjacent thereto, the end of the paper forming the body being folded inwardly into engagement with the flange of the closure and into the recess thereof, and a plastic filler introduced into the recess of the closure to hold and lock the inturned end portion of the body into tight face- 20 wise engagement with the flange of the closure 25 and the flange of the closure into like tight engagement with the body, a portion of the closure extending on a plane with the end of the body after the portion thereof has been turned in- 30 wardly.

5. A container including a paper body, a closure adapted to be inserted in an end of the body, said closure including opposed wall portions forming a channel therebetween, the end of the paper forming the body being folded inwardly around 35 the end of one of the wall portions of the closure and into engagement with the inner face thereof, and a separate filler introduced into the channel to engage the opposite wall portion of the closure and the inturned portion of the body, said filler holding the inturned portion of the body in tight facewise engagement with the face of its associated wall portion of the closure and the wall portion of the closure in like tight engagement with the body. 40

6. A container including a paper body, a closure adapted to be inserted in an end of the body, said closure including opposed wall portions forming a channel therebetween, the end of the paper forming the body being folded inwardly around 50 the end of one of the wall portions of the closure and into engagement with the inner face thereof, and a plastic filler introduced into the channel to engage the opposite wall portion of the closure and the inturned portion of the body, said filler holding the inturned portion of the body in tight facewise engagement with the face of its associated wall portion of the closure and the wall portion of the closure in like tight engagement with the body. 55

7. A container comprising a body portion having an inturned flange spaced from the wall of the body, and a closure portion having a flange interfitting therewith, the adjacent surfaces of the interfitting portions having a coating of 65 paraffin or the like, the closure portion being formed and related with reference to said interfitting portions to provide a recess and a filler in said recess operating to hold the interfitting portions in facewise engagement and in ad- 70hering sealed condition derived from applying the filler in heated state causing melting of the said paraffin or the like on the interfitted portions and consequent adhesion thereof.
